PORATION OF PENNSYLVANIA

ELECTRIC SWITCH

Application filed April 18, 1922. Serial No. 555,386.

Our invention relates to electric switches and particularly to those of the type wherein a thermal cutout or release mechanism is employed.

- 5 Our invention has for its object the provision of means whereby a switch may be caused to assume an open position upon the occurrence of a predetermined condition in the circuit controlled by the switch.
- 10 A further object of our invention is to simplify and improve generally the construction of push-button switches.

As shown in the accompanying drawings, Figure 1 is a plan view, of a switch embodying our invention, a portion of the cover being broken away,

Fig. 2 is a view thereof in side elevation, the casing being shown in section,

Fig. 3 is a detail view of the latch-actuating mechanism,

Fig. 4 is a diagrammatic view illustrating the manner in which the switch is connected to the circuit, and

Fig. 5 is an edge view of the latch-actuating member and its actuating springs.

The switch is mounted in a casing 6 that is provided with a cover 7 through which push buttons 8 and 9 project, the push button 8 being normally biased outwardly by a flat spring 10.

A base 12 is mounted within the switch box 6 and serves as a support for a pair of stationary contact members 13 and for a pair of movable contact members 14.

35 The movable contact members 14 are provided with terminal members 15 and 16 and are carried by a bracket 18, through a cross-head 19 of insulating material.

The bracket 18 is pivotally supported upon two posts 21 and its outer end is normally biased upwardly by a tension spring 22.

The bracket 18 is engaged, at one end, by a latch 23 that is normally biased inwardly by a spring 24. The latch 23 is provided with a cam surface that is engaged by the lower end of the push button 8 when it is desired to effect an opening of the switch manually. The push button 9 is employed for returning the contact members 14 to closed position, against the tension of the

spring 22. It will be observed that the latch will be snapped into locking engagement with the bracket 18, whenever the contact members 14 are moved to closed position.

A latch-actuating member 27, such as a notched collar, is supported by a shaft 28 that is carried in a bracket 28a which is fastened to the base 12. The shaft 28 is in series with the circuit 29 that is controlled by the switch (see Fig. 4) and is of resistance material so that it will become heated during the presence of an abnormal current in the circuit.

The member 27 is normally held against turning movement on the shaft 28 by reason of a fusible material, or solder 30. (Fig. 3.) However, upon an abnormal or predetermined increase of current in the circuit, the resistance member 28 becomes heated and the fusible material 30, is softened, to permit turning movement of the member 27, under the action of one of the springs 31 and 32, each of which has its ends secured to the bracket 18 and the member 27, respectively.

In the position shown in Fig. 2, the spring 31 is under tension and the actuating member 27 is in set position. If, now, the fusible member 30 be softened, as has been explained, the member 27 will be turned in a clockwise direction, tripping the latch 23 clear of the bracket 18. This operation permits the bracket 18 to be moved about its pivot, by the spring 22, in a clockwise direction. During this movement, the tension of the spring 31 is lessened and that of the spring 32 increased, thus causing the actuating member 27 to then move in a counter-clockwise direction to its set position, as shown in Fig. 2. A shouldered portion 27a, together with the upstanding portion of the bracket 28a, serves to limit this movement of the member 27.

It will be understood that, upon tripping the latch 23, the movements just described occur in rapid sequence, so that the member 27 is returned to set position before the fusible member 30 has had sufficient time to become cool.

From the foregoing, it will be seen that we provide a switch that is readily operable either automatically or manually and one

wherein repeated operations will not affect the operativeness thereof.

Various modifications in detail and general arrangement may be made without departing 5 from the spirit and scope of the invention as defined in the accompanying claims.

We claim as our invention:

1. The combination with a circuit interrupter that is normally biased to one position, of a latch for holding the interrupter in another position, a shaft mounted in fixed 10 position, a thermally-controlled element rotatably mounted thereon and adapted to release the latch under predetermined conditions,

means actuated by the movement of the interrupter to return the said element to its former position after each actuation thereof and manually operable means for tripping the latch.

2. The combination with a circuit interrupter that is normally biased to one position, of a latch for holding the interrupter in another position, a shaft associated with the circuit interrupter, a thermally-controlled element rotatable on the shaft to release the latch under predetermined conditions, and a tension device actuated by the movement of the interrupter to return the said element to its former position during 30 each opening movement of the interrupter.

3. The combination with a movable switch member normally biased towards one position, of a latch for holding it in another position, an actuating member for the latch, a tension member for moving the said member to trip the latch, a tension member for returning the actuating member to its starting position, and means whereby the effective force of the said tension members is 35 varied upon movement of the said switch members.

4. The combination with a movable switch member normally biased towards one position, a latch for holding it in another position, an actuating member for the latch, a tension member for moving the said member to trip the latch, a tension member for returning the actuating member to its starting position, and means whereby the tension 45 members are alternately caused to move the actuating member as the said switch member is moved back and forth.

5. The combination with a movable switch member normally biased towards one position, a latch for holding it in another position, an actuating member for the latch, a thermal element for holding the actuating member against movement under predetermined conditions, a tension member for 50 moving the said member to trip the latch, a tension member for returning the actuating member to its starting position, and means whereby the effective force of the said tension members is varied upon movement of the said switch member.

6. The combination with a movable switch member normally biased towards one position, a latch for holding it in another position, an actuating member for the latch, a thermal element for holding the actuating member against movement under predetermined conditions, a tension member for moving the said member to trip the latch, a tension member for returning the actuating member to its starting position, and means whereby the tension members are alternately caused to move the actuating member as the said switch member is moved back and forth.

7. The combination with a circuit interrupter that is normally biased to one position, of a latch for holding the interrupter in another position, means for manually tripping the latch, a shaft mounted in fixed position, a thermally-controlled element fixed to the shaft adapted to be freed therefrom to automatically release the latch under predetermined conditions, and means actuated by the movement of the interrupter to return the said element to its former position after each automatic operation thereof.

8. The combination with a movable switch member normally biased toward open position, of a latch for holding it closed, a fusible element, a tensioned member normally held by the fusible element, a resistance member in the circuit controlled by the switch to effect heating of the fusible element, means for tripping the latch upon release of the said tensioned member, and means for returning the said member to set position after the latch has been tripped.

9. The combination with a movable switch member normally biased toward open position, of a latch for holding the switch member in closed position, a thermally-actuated and automatically resettable fusible element for tripping the latch, a resistance for heating the thermal element and means for manually tripping the latch.

10. The combination with a movable switch member normally biased toward open position, of a latch for holding it in closed position, a thermally-actuated element for tripping the latch, means for exerting a tensional force upon the said element, and means for shifting the direction of tensional force at each operation of the switch.

11. The combination with a movable switch member normally biased toward open position, of a latch for holding the switch member in closed position, a thermally-controlled element for tripping the latch, means actuated by the said movable member for resetting the said element, and means for manually tripping the latch.

12. In a switch, a shaft, a latch member mounted on the shaft, a plurality of springs attached to the latch member to exert different turning moments about the shaft, and

anchoring means for the springs, one of the springs normally being in a stressed condition and another spring normally being in an inactive condition whereby, upon the actuation of the latch member by the first 5 spring, the second spring is partially stressed to return the member to its initial position.

13. In combination, a shaft, a latch member mounted thereon, a plurality of springs 10 attached to said member at different peripheral points, anchoring means for the springs, and latching means for the member, one of the springs normally biasing the member to movement upon the release of the latch, another 15 spring being stressed during the operation of the first spring for retrieving the member.

14. The combination with a movable switch member normally biased towards one 20 position, of a latch for holding it in another position, an actuating member for the latch comprising a collar soldered to a shaft, a tension member for moving the collar to trip the latch upon the softening of the solder, 25 and a second tensioning member for returning the collar to its initial position after the latch is tripped and before the solder becomes hardened.

In testimony whereof, we have hereunto 30 subscribed our names this 17th day of April, 1922.

HAROLD G. BAXTER.
FRED VON HOORN.
